METHOD FOR ZONE HARDENING

Francis S. Denneen, Cleveland, and William C. Dunn, Shaker Heights, Ohio, assignors to The Ohio Crankshaft Co., Cleveland, Ohio, a corporation of Ohio

Original application December 31, 1935, Serial No. 56,870. Divided and this application March 30, 1940, Serial No. 326,946

5 Claims. (Cl. 148—10)

The present invention, relating as indicated to a method for zone hardening, is a division of our co-pending application No. 56,870, filed December 31, 1935, for Apparatus for zone hardening.

We have found that utilization of the various apparatuses and methods for zone hardening heretofore made available are somewhat unsatisfactory particularly when such zones terminate in magnetically permeable neighboring elements. To be more specific, where the zone under consideration is the journal of a crankshaft, the arms or cheeks thereof cause undesirable distribution of the magnetic flux which is induced in inductive heating.

The primary object of this invention has been to provide a method for uniformly hardening a zone the neighboring elements of which are magnetically permeable. A further object of this invention has been to provide apparatus for practicing a method of the character described which is capable of being accurately and quickly set-up.

To the accomplishment of the foregoing and related ends, said invention, then, consists of the means hereinafter described and particularly pointed out in the claims; the annexed drawing and the following description setting forth in detail one method constituting, however, but one of various applications of the principle of our invention.

In said annexed drawing:

Fig. 1 is an end view partially fragmentary and partially sectional of apparatus for practicing this invention; and

Fig. 2 is a partially fragmentary section taken on the line 2—2 of Fig. 1.

Figs. 1 and 2 show a specific application of this invention to a crankshaft crankpin which is to be hardened. The crankshaft, which is fragmentarily shown, comprises main bearings 10, pin 11 and interconnecting cheeks 12. It is to be understood that "crankshaft" is used herein by way of illustration and not limitation. The inductor members 14 and 15 have jackets 17 and 18 attached by screws 20 and 21. Suitable insulation gaskets 23 of rubber or other resilient material serve as means for preventing loss of the quenching medium and to confine the flow of current to the inductor members adjacent to the pin. The lower inductor member 15 is attached by means of bolt 25 to the extension 26 which is supported by the pin 28 and the upper inductor member 14 is attached to the hinge member 29 by means of bolts 30. The hinge

member 29 is adapted to rotate about hinge pin 32 which is carried in the stationary hinge member 33. Extension 26 and stationary hinge member 33 are attached to stationary bus bars 35 and 36 respectively by bolts 37 and 38, these bus bars being attached preferably by fusion to the ends of the single coil secondary 39 of the transformer. The primary turns indicated by the fragment 39' are insulated from each other and from the secondary by suitable means. To relieve the bus bars 35 and 36 from strains which would occur in the manipulation of the inductors both pins 28 and 32 have their ends supported in the frame carrying the coils and other related parts, and which is not shown.

In applying the inductor members to the crankshaft bearing or pin 11, an insulating space 40 between these inductors and their supports is provided. This space is usually maintained at 20 a minimum to prevent losses and ordinarily is of the order of one sixteenth of an inch. The outer ends 41 and 42 of the inductor members are brought into firm conducting contact to complete the circuit around the shaft. Usually the 25 voltage is low and the current density is very high at this contact so that very slight difference in the contact resistance at different points in the contacting area will cause serious variation in the current density from one side to the other of the inductor members. This causes corresponding and objectionable variation in the rate of heating in different sections in the zone to be heated. To insure uniformly high conducting contact, we usually attach silver contact strips 35 44 and 45 to the said outer ends and provide a C clamp 46 for clamping the same together. For some purposes, it is satisfactory to omit these silver strips and to use instead a piece of fine mesh hard copper or bronze gauze coated or 40 impregnated with an amalgam containing tin, zinc, copper or other suitable metal.

As a general thing, satisfactory results may be obtained by having the surface of the inductor parallel to the surface to be heated. In some 45 cases with this parallel arrangement, however, the heating is more rapid opposite the center portion of the inductor, resulting in greater depth of hardened zone in the center section of the width of the bearing. To correct this condition so as to make the depth of the hardened zone approximately uniform across the width of the bearing, we frequently recess the face of the inductor member bringing it further away from the surface to be heated at the place where a 50 parallel inductor member would tend to create

excessive or objectionable depth in the hardened zone. This recessing is indicated at 47 in Fig. 2 and provides a surface zone of substantially uniform depth when other related conditions are favorable. Frequently, however, neighboring elements may disturb the desired distribution of the magnetic flux such, for instance, as the arms or cheeks 12 of the crankshaft. To compensate for the presence of these elements the pin 11 is placed in an eccentric position relative to the inductors so that the least clearance between the inductor members and shaft is between the arms or cheeks. For most satisfactory results, it has been found that for journals having a diameter of approximately two and one-half inches, the clearance at 48 should be of the order of .080 of an inch, at 49 it should be .040 and at 50 and 51 .060. Small cylindrical spacers made of lava or other insulating material as shown at 53 are usually inserted to insure the desired spacing.

Other forms may be employed embodying the features of our invention instead of the one here explained, change being made in the form or construction, provided the elements stated by any of the following claims or the equivalent of such stated elements be employed, whether produced by our preferred method or by others embodying steps equivalent to those stated in the following claims.

We therefore particularly point out and distinctly claim as our invention:

1. In a method of equalizing heating of a periodically varying flux field in a surface zone of a journal, the journal having a substantially radially extending arm in proximity with one end thereof, the steps comprising placing an inductor in embracing relation with the journal and in proximity with the arm, the inductor being spaced from the surface zone of the journal and from the arm, the inductor being shiftable transversely of the journal so that the space between the inductor and the journal on the arm adjacent side of the journal can be made substantially less than the space between the inductor and the journal on a diametrically opposite side of the journal, supplying periodically varying current to the inductor to induce current in the journal and in the proximate arm, the current being induced in the arm effecting a shifting of the flux field in the journal to reduce heating in the arm adjacent side of the journal, and reducing the space between the inductor and the journal on the said arm adjacent side of the journal by shifting the inductor relatively to the journal sufficiently to substantially overcome the shifting of the flux field in the journal to substantially equalize heating in the diametrically opposite sides of said journal.

2. In a method of equalizing heating of a periodically varying flux field in a surface zone of a journal, the journal having a substantially radially extending arm in proximity with one end thereof, the steps comprising placing an inductor in embracing relation with the journal and in proximity with the arm, the inductor being spaced from the surface zone of the journal and from the arm, the inductor being shiftable transversely of the journal so that the space between the inductor and journal on the arm adjacent side of the journal can be made substantially less than the space between the inductor and the journal on a diametrically opposite side of the journal, supplying periodically varying current to the inductor to induce current in the journal and in the proximate arm, the current being

induced in the arm effecting a shifting of the flux field in the journal to reduce heating in the arm adjacent side of the journal, and reducing the space between the inductor and the journal on the said arm adjacent side of the journal by shifting the inductor relatively to the journal so that the said space between the inductor and the journal on the arm adjacent side of the journal will be substantially one half of the space between the inductor and the journal on the side of the journal opposite to said arm to substantially equalize heating in the diametrically opposite sides of the journal.

3. In a method of equalizing heating of a periodically varying flux field in a surface zone of a journal, the journal having a substantially radially extending arm in proximity with one end thereof, the steps comprising placing an inductor in embracing relation with the journal and in proximity with the arm, the inductor being spaced from the surface zone of the journal and from the arm, the inductor being shiftable transversely of the journal so that the space between the inductor and the journal on the arm adjacent side of the journal can be made substantially less than the space between the inductor and the journal on a diametrically opposite side of the journal, supplying periodically varying current to the inductor to induce current in the journal and in the proximate arm, the current being induced in the arm effecting a shifting of the flux field in the journal to reduce heating in the arm adjacent side of the journal, and reducing the space between the inductor and the journal on the said arm adjacent side of the journal by shifting the inductor relatively to the journal so that the said space between the inductor and the journal on the arm adjacent side of the journal will be of the order of three sixty-fourths of an inch and the space between the inductor and journal on the side of the journal opposite to said arm will be of the order of five sixty-fourths of an inch to substantially equalize heating in the diametrically opposite sides of the journal.

4. In a method of equalizing heating of a periodically varying flux field in a surface zone of an article, the article having a projecting member adjacent to the surface zone, the steps comprising placing an inductor in substantially closely spaced relation with the surface zone to induce heating current in the zone, and then shifting the inductor to provide a non-uniform spacing of the inductor and the article to effect a uniform heating of the surface zone.

5. In a method of equalizing heating of a periodically varying flux field in a surface zone of an article, the article having a projecting member adjacent to the surface zone, the steps comprising providing an inductor adapted to encircle a part of the article, the inductor having spaced terminals attached thereto, bringing the inductor into encircling relationship with the article, locating the space between the terminals of the inductor at a point substantially on an opposite side of the article to the aforesaid projecting member, then shifting the inductor to bring a part of the inductor into closer relation with a side of the article adjacent to the projection and to bring another part of the inductor into more distant relation with an opposite side of the article to substantially equalize heating in the said sides of the article, and supplying inducing current to the terminals of the inductor.
